(57) **CLAIM**

The ornamental design for POS base having a support, as shown and described in the drawings.

DESCRIPTION

FIG. 1 is a perspective view of the POS base having a support showing our new design.

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof.

The broken lines showing the cable portions depict environment only and form no part of the claim, while all other broken lines depict portions of the POS base having a support that form no part of the claimed design.
